UNITED STATES PATENT OFFICE.

CLAUDE C. PRALL, OF TRENTON, NEW JERSEY, ASSIGNOR, BY MESNE ASSIGNMENTS, TO THE ANGLO-AMERICAN PATENT BOTTLE COMPANY LIMITED, OF LONDON, ENGLAND.

NON-REFILLABLE BOTTLE.

1,155,616.

Specification of Letters Patent.

Patented Oct. 5, 1915.

Application filed December 31, 1910. Serial No. 600,260.

To all whom it may concern:

Be it known that I, CLAUDE C. PRALL, a citizen of the United States, residing at Trenton, county of Mercer, and State of New Jersey, have invented certain new and useful Improvements in Non-Refillable Bottles, fully described and represented in the following specification and the accompanying drawings, forming a part of the same.

10 This invention relates to improvements in so-called non-refillable bottles and particularly to bottles of this class in which the neck is made in a separate piece from the bottle body and secured thereto by suitable means.

15 It is the object of the present invention to provide a bottle neck of this kind which may be economically manufactured and in which the necessary baffle mechanism, valve 20 mechanism and valve closing mechanism may be economically and quickly introduced and positioned.

25 As a full understanding of the invention can best be had from a description of a bottle neck embodying the same such a description will now be given reference being had to the accompanying drawing in which—

30 Figure 1 is a vertical elevation of a bottle equipped with a neck embodying the present invention, and Figs. 2, 3 and 4 are transverse sections of the bottle neck on the lines 2, 3, 4 respectively of Fig. 1.

35 Referring to said drawings 1 represents the bottle body, 2 the neck thereof and 3 a stopper for the latter, which of course may be of any suitable material. The bottle neck 2 is separable from the bottle body being secured thereto by a metal collar 4 spun around the base of the neck and the upper 40 end of the body and interlocked therewith by depression into annular recesses or grooves 5 suitably formed therein, a gasket 6 of suitable material being interposed between the abutting edges of the bottle neck 45 and body to form a tight joint. Before the bottle neck is thus secured to the bottle body the valve and baffle mechanisms are of course introduced into the neck. This method of making non-refillable bottles is one which 50 has recently been adopted in the commercial production of such bottles because of economy in manufacture and because of the ease and facility with which the valve and baffle mechanisms may be introduced into the bottle neck and then tested before being secured

to the bottle body. In the commercial manufacture of the necks, however, it has been found necessary, in order to provide for the introduction and accurate positioning of the valve and baffle mechanisms, to make the bottle neck in two transverse parts or sections, then introduce the baffle mechanism, and then secure the two parts or sections together, valve mechanism being finally introduced from the lower end of the neck. I 60 have discovered, however, that this may be avoided and a great saving of time and labor effected. This I do by making the neck of porcelain or other suitable moldable material and, in forming it, providing it with a 65 valve chamber 7 and above the latter with an integral contracted portion 8 having a depending part 9 the inner diameter of which is considerably less than that of the valve chamber. This contracted and depending portion forms part of the baffle mechanism preventing the introduction into the valve chamber 7 of wire or any other 70 valve tampering instrument and it also acts as a stop and positioning device for the baffle 75 plug 10 which is introduced into the bottle neck from the lower end thereof and dropped or shoved by hand into proper position therein. The baffle plug 10 is molded 80 from porcelain or other suitable material 85 and is provided on its periphery with longitudinal ribs 11 engaging the walls of the valve chamber 7. These ribs 11 extend beyond the upper end of the plug as at 12, so as to engage the contracted portion 8 of the 90 bottle neck and thus properly position the plug in valve chamber 7. The spaces between the ribs 11 at the sides of the plug provide longitudinal openings for the passage 95 of liquid between the plug and the walls of the valve chamber while the spaces between the extensions 12 of the ribs provide lateral openings for the passage thence of the liquid. These several openings provide tortuous passages into which a wire or other 100 valve-tampering instrument cannot be introduced.

To further guard against the introduction of a valve tampering instrument the upper end of plug 10 is provided with a 105 recess 13 in line with, but of larger diameter than, the depending part 9 of the contracted portion 8 of the bottle neck, and as such depending part 9 is in about the same horizontal plane as the upper edge of the plug 110

it is obvious that the difficulties in the way of introducing a wire or the like into the openings between the plug 11 and the walls of the valve chamber are very considerably increased. The lower end of the plug 11 is also recessed for the reception of a valve closing weight 14 and below the plug the valve chamber is of suitable size and shape for the reception of a valve 15 and valve rest 16 which with the weight 14, are of course introduced into the bottle neck after the plug 10 has been introduced and before the neck is secured by means of the collar 4 to the bottle body. The plug 10 is secured in place in the bottle neck by first dipping it into a bath of porcelain or other suitable material, then dropping or shoving it into position in the bottle neck, and then suitably heating the neck and plug to anneal the latter to the former. This, of course, is all done before the introduction of the weight 14, valve 15 and valve rest 16.

What is claimed is:—

1. A bottle neck arranged to be connected to a bottle-body and comprising an integral outer member having a stopper receiving chamber at the upper end, an enlarged chamber extending to the lower end of the neck, a seat receiving rabbet in its lower edge, and an integral inwardly and downwardly flanged deflector intermediate the stopper chamber and the enlarged chamber and forming a constricted passage between said chamber, in combination with a valve seat arranged to fit in the seat receiving rabbet, a valve loosely mounted upon the valve seat, a non-integral baffle device fitting the enlarged chamber below the deflector and

arranged to be cemented therein, said baffle having recesses on its upper and lower surfaces and liquid passages in its periphery, and a weight loose within the enlarged chamber between the bottom of the baffle and the top of the valve. 40

2. A bottle neck arranged to be connected to a bottle-body and comprising an integral outer member having a stopper receiving chamber at the upper end, an enlarged chamber extending to the lower end of the neck, a seat receiving rabbet in its lower edge, and an integral inwardly and downwardly flanged deflector intermediate the stopper chamber and the enlarged chamber and forming a constricted passage between said chamber, in combination with a valve seat arranged to fit in the seat receiving rabbet and provided with a downward extending portion arranged to enter the top of the bottle and form a dowel connection between the neck and bottle, a valve loosely mounted upon the valve seat, a non-integral baffle device fitting the enlarged chamber below the deflector and arranged to be cemented therein, said baffle having recesses on its upper and lower surfaces and liquid 50 passages in its periphery, and a weight loose within the enlarged chamber between the bottom of the baffle and the top of the valve. 55

In testimony whereof, I have hereunto set my hand, in the presence of two subscribing 70 witnesses.

CLAUDE C. PRALL.
